UNITED STATES PATENT OFFICE.

GEORGE W. DOVER, OF PROVIDENCE, RHODE ISLAND, ASSIGNOR TO DOVERCRAFT COMPANY, INC., OF PROVIDENCE, RHODE ISLAND, A CORPORATION OF RHODE ISLAND.

CURTAIN FIXTURE.

Application filed January 14, 1927. Serial No. 181,039.

This invention relates to a novel form of curtain fixture of simple and inexpensive construction which is however exceptionally strong, and which is adapted to sustain the usual strains to which devices of this character are subjected without bending or distortion.

Heretofore, devices of the general character of that shown herewith, that is, telescoping curtain rods formed of channel shaped sheet metal, have been of exceedingly flimsy construction and easily bendable from handling as well as liable to distortion in applying curtains thereto or in removing curtains therefrom. Such devices have been made generally for direct application to hooks or other supporting structures and from the extremely thin character of the metal used they have been liable to such binding and distortion that the ends thereof could be secured to the attaching devices only with the greatest difficulty.

One object of the present invention is to overcome the difficulties enumerated above and provide an exceptionally firm and rigid construction wherein the parts are not liable to become bent or distorted by ordinary usage, as well as to provide means for securing the same to attaching brackets in such a manner as to obviate the liability for the attaching means to become distorted as has been the case previously in devices of this character.

Another object of the invention is to provide proper and adequate reinforcing means for that portion of the rod structure which sustains the greatest strain, and which consequently is most liable to distortion, by providing a reinforcement which extends throughout the entire cross-sectional extent of that portion of the rod to which it is applied, and preferably to extend such reinforcement through that portion of the rod which is usually bent inwardly towards the window casing.

A further object of the invention is to provide suitable attaching means in conjunction with the reinforcing means for attaching the rod to a window casing and thus avoiding the liability of that portion of the rod which is attached to the bracket from becoming so bent or distorted as to prevent the rod from being readily placed in position on the bracket, which attaching means is so formed as to retain either sec-

tion of the rod in normal curtain supporting position when the other section has been removed.

Other objects and advantages of the invention relate to various novel features of construction and improved arrangement of the parts as well as improved methods of operation as will be more fully set forth in the detailed description to follow.

In the drawings forming a part of this application:—

Fig. 1 is a front elevational view of a window casing showing my improved curtain fixture in position thereon, only one of the rods being shown for simplicity in illustration,

Fig. 2 is a perspective view of a portion of one of the curtain rods,

Fig. 3 is a perspective view of one form of bracket member which may be employed, illustrating the manner of securing one end of a curtain rod thereto, and,

Fig. 4 is a perspective view of a modified form of bracket.

Referring to the drawings; 1 designates the top of a window casing to which are secured brackets 2 by means of screws or similar fastening devices 3, passed through openings 4 in the horizontal portions 5 of said brackets and into the upper edge of the casing in such a manner as to retain the vertical portions 6 of the brackets in proper position in front of the top of the window casing.

Each bracket 2 is provided with a plurality of lugs 7, in the present instance three in number although a greater or less number of said lugs may be employed as may be desired in use. In the present embodiment of the invention each lug 7 is struck out from the body portion of the bracket, although I am aware that the lugs and brackets may be formed in various ways, and that other forms of brackets and lugs may be employed with my improved rod. The lower edge of each lug is formed integral with the body portion of the bracket in the present instance, and the side edges 8 of each lug are substantially vertical for a purpose which will be referred to hereafter.

A curtain rod, indicated generally by the numeral 10, is shown in its operative position as secured to the brackets in Fig. 1, and comprises a pair of channel shaped

sheet metal body portions 11 and 12, the free end of the body portion 11 telescoping within the free end of the body portion 12. The manner of forming the reinforcing strip 15 as applied to the channel shaped body portion 12 and the mode of securing the same to the body portion 12 will now be described, it being understood that a similarly constructed reinforcing strip is similarly secured to the body portion 11.

A flat reinforcing strip 15 has one end inserted in one end of the channel shaped body portion 12 and that part of the body portion surrounding the flat reinforcing strip fits closely about the strip so that the flat reinforcing strip extends entirely across the channel opening in the body portion and provides a reinforcement therefor throughout the entire cross-sectional extent of that part of the body portion occupied by the flat reinforcing strip.

In the present instance the metal of the body portion 12 is shown as being drawn about the flat reinforcing strip 15 to reduce somewhat the cross-sectional area of the body portion about the reinforcing strip over that throughout the remainder of its extent, thus both drawing it closely about the reinforcing strip and leaving a channeled opening of slightly greater area at the opposite end thereof for the reception of the free end of the body portion 11, although, if desired, the parts may be so proportioned that the reinforcing strip will normally fit closely within the body portion upon being forced therein. It is entirely immaterial to the carrying out of my invention whether that part of the channel shaped body portion surrounding the reinforcing strip be reduced or whether the reinforcing strip be made of such size that when forced into the channel of the body portion the latter will fit closely therearound, it being clearly understood that I may employ any desired method for fitting the reinforcing strip within the channel of the body portion.

That end of the reinforcing strip 15 which enters the channel body 12 is shown as terminating at 16, although in practice the reinforcing strip may extend for a greater or less distance therein as desired, provided that suitable space remains for the free end of the body portion 11 to give the rod the desired degree of extension. The channeled body portion 12 and reinforcing strip 15 are bent inwardly towards the window casing as at 17, which bend serves to positively retain the reinforcing strip and body portion against separation, and the reinforcing strip by extending beyond the bend 17 strengthens the rod throughout that portion of its extent which is ordinarily subject to the greatest strain.

The free end portion of the reinforcing

strip 15 is bent at substantially right angles at 18, the bent end 19 being provided with a slot 20 formed in the lower edge thereof closely adjacent to the bend 18, the slot 20 being of suitable width to receive one of the lugs 7 so that the base of the lug will enter the slot 20 and one vertical edge 8 of the lug 7 will bear against that portion of the reinforcing strip adjacent to the bend 18 as at 22 thereby forming a bearing and holding the rod 10 in normal horizontal position even when the free end thereof is unsupported, as by removal of the body portion 11. In this way one section of the rod, and the curtain carried thereby may be so removed from the window, and the other section, by reason of its rigid construction and the improved attaching means, will maintain itself in position and continue to support any reasonable weight without bending and without turning upon the bracket.

The provision of the slot 20 also results in lowering the rod so that the extreme lower edge 23 of the end portion 19 and the lower edge 29 of the rod bear against the bracket 2 below the lower edge of the lug 7 thus producing a more firm and rigid structure against the outward strain against the lug 7 than would be the case if the slot were omitted.

In Fig. 4 of the drawings I have shown a slightly modified form of bracket 24 having a horizontal portion 25 and a vertical portion 26 with openings 27 formed in the horizontal portion 25 for securing the same to the top of a window casing. The bracket 24 is provided with struck out lugs 28 arranged in horizontal order and each provided with vertical edges 29 adapted to engage with that portion of a reinforcing strip 15 adjacent to the bend 18 therein to form a bearing for supporting a section of the rod against turning about the bracket.

My improved curtain fixture as above described is capable of use under all of the various conditions in which devices of this character are employed, and may be used singly or in multiple for supporting one or more draperies. As stated above my improved construction produces a support possessing a high degree of rigidity and one which is not liable to become bent or distorted under ordinary conditions of use, while at the same time providing a novel attaching means for securing the same to a casing which not only provides a firm securing means but greatly facilitates the removal of curtains therefrom and replacement of curtains thereon.

What I claim is:

1. In a curtain fixture, a rod comprising a channel shaped sheet metal body portion provided with a reinforcing strip about which the sheet metal body portion is pressed to retain the reinforcing strip therein and

provide a reinforcement for the sheet metal body portion throughout the entire cross-sectional extent thereof, one end of said reinforcing strip being shaped to engage a bracket, and a bracket provided with means for releasably engaging the end of said reinforcing strip.

2. In a curtain fixture, a rod comprising a channel shaped sheet metal body portion provided at one end thereof with a flat reinforcing strip extending entirely across the interior of the channel shaped cavity and about which the sheet metal body portion is drawn to provide a reinforcement for the sheet metal body portion throughout the entire cross-sectional extent thereof, said body portion and reinforcing strip having a common bend formed at one point in their longitudinal extent.

3. In a curtain fixture, a telescoping rod comprising a pair of channel shaped sheet metal body portions, one end of one of said body portions telescoping within one end of the other body portion, and flat reinforcing strips located within the opposite ends of said body portions and extending entirely across the channeled openings therein to provide reinforcements for the body portions throughout the entire cross-sectional extent thereof, that part of each body portion surrounding the flat reinforcing strip fitting closely about the said strip to increase the effectiveness of the reinforcement and tend to prevent separation of the body portion and strip.

4. In a curtain fixture, a telescoping rod comprising a pair of channel shaped sheet metal body portions, one end of one of said body portions telescoping within one end of the other body portion, and flat reinforcing strips located within the opposite ends of said body portions and extending entirely across the channeled openings therein to provide reinforcements for the body portions throughout the entire cross-sectional extent thereof, that part of each body portion surrounding the flat reinforcing strip fitting closely about the said strip to prevent separation.

ration of said body portion and strip and said body portion and strip being bent at 50 one point in their longitudinal extent.

5. In a curtain fixture, a rod comprising a flat metal strip having the end portion thereof bent at substantially right angles to the adjacent part thereof and provided with 55 a slot formed in the bent end thereof close to the bend, and a bracket provided with a lug having an edge engageable by the bent end of said strip to position the lower portion of said lug within the slot in said strip whereby the edge of said lug will bear against that portion of the strip adjacent to the bent end thereof and form therewith a bearing to prevent tilting of said rod when the opposite end of the rod is unsupported. 65

6. In a curtain fixture, a rod comprising a channel shaped sheet metal portion provided with a reinforcing strip about which the sheet metal body is pressed to provide a reinforcement for the sheet metal body 70 portion throughout the entire cross-sectional extent thereof, the free end of said strip being inturned and provided with a slot located adjacent to the bend, and a bracket provided with a projecting lug adapted to 75 fit within the slot in said strip and having an edge contacting with the strip adjacent to the bend therein to firmly support the rod in substantially horizontal position.

7. A curtain fixture comprising a bracket 80 provided with an outwardly projecting lug, a curtain rod having a flat end portion bent at substantially right angles to the part of said rod adjacent thereto and provided with a slot formed in the lower edge thereof adjacent to the bend, the slot being of suitable width to receive the projecting lug so that one edge of said lug will engage a portion of the rod adjacent to the bend and serve as a bearing therefor to maintain said rod in 85 substantially horizontal position when the opposite end thereof is unsupported. 90

In testimony whereof I have affixed my signature.

GEORGE W. DOVER.
